UNITED STATES PATENT OFFICE.

EDWIN GOODALL, OF NEW YORK, N. Y.

CHECK, DRAFT, OR MONEY-ORDER.

SPECIFICATION forming part of Letters Patent No. 373,734, dated November 22, 1887.

Application filed May 10, 1887. Serial No. 237,724. (No model.)

To all whom it may concern:

Be it known that I, EDWIN GOODALL, a citizen of the United States, residing at New York, in the county of New York and State of New York, have invented new and useful Improvements in Checks, Drafts, or Money-Orders, of which the following is a specification, reference being had to the accompanying drawing.

This invention relates to improvements in checks or drafts for exchange or transfer of money, the object of which is to prevent the amount originally placed on the check or draft from being altered, all of which will be herein-after more fully described, and pointed out in the claim.

In the accompanying drawing, forming part of this specification, the several columns of figures and numbers on the left-hand side, together with the maximum denomination of fifty dollars and the three asterisks in the panel at the top extending across those columns, are so arranged relative to each other that when the specified amount of dollars and cents has been indicated on the several columns the remaining part of each column is to be torn or cut away, so that there is no possibility that the numbers can be raised to a larger sum without immediate detection.

In the drawing, which represents a check for the sum of thirty-five $\frac{25}{100}$ dollars, A is a panel having within it three asterisks, a b c. a represents cents, b represents units, and c represents tens, and, as shown, the corresponding figures indicate each of these—viz., 3 for tens, 5 for units, and 25 for cents, placed at c b a, correspondingly. The amount of the check to be paid is thirty-five dollars and twenty-five cents.

The four horizontal divisions represented at B have in them the figures 1, 2, 3, 4, and the rectangular space C to their right has in it the large cipher 0, which is common to these figures, as 1 and 0 reads ten dollars, 2 and 0 reads twenty dollars, &c. At D, immediately below the numbers 1, 2, 3, 4, is a column in which is printed the highest amount for which the check or draft can be issued, and when so issued of course no raising can be done. At E, below the cipher, are the printed numbers from 1 to 9, included, which represent only units of dollars, as one dollar, &c. The blank column F to the right is for inserting in ink the amount

of cents, as 25, (seen at f,) which will be written opposite the unit indicated in column E. The dotted line commencing at the bottom of column E to the right of 9, extending up to 5, thence below it to the division line between E and D, and thence along this line up to the line between 3 and 4 in B to the exterior line is designed to show the lines of cutting to sever the check for the particular amount thereof. When the part thus described shall have been separated from the body of the check, it will be observed that the figures 3 in B and 5 in E are the highest numbers remaining and signify thirty-five dollars, the 25 for cents being written in F. These correspond with the figures 3, 5, 25 on the asterisks in the panel A at the top. There is no place whatever in the remaining part where raised numbers can be attached by insertion.

For amounts less than tens—as, for instance, for five dollars—the line of the cut must be continued along the division-line between E and D all the way up between the asterisks c 75 and b, so that no tens can be added to the five.

The part lettered H is the remitters' receipt, to be retained by the remitter or person buying the check or draft, as is usual in such transactions, and G is the body of the check, draft, or money-order, which parts are not new nor claimed by me; and I do not claim, broadly, the use of columns of figures, some parts of which are to be severed from the main check, having the proper amounts specified in the body 85 of the check; but

What I claim is—

A check, draft, or money-order provided with the columns B E F, and a panel, A, with asterisks a b c, arranged immediately above the columns, and having printed in column B the figures 1, 2, 3, 4, representing tens, and in letters below these the maximum amount, in column E a zero, and below this zero printed units from 1 to 9, included, the column F being blank for writing in ink the amount of cents opposite to the unit figure of the check.

In testimony that I claim the foregoing as my own I hereto affix my signature in presence of two witnesses.

EDWIN GOODALL.
